UNITED STATES PATENT OFFICE.

HARRY H. BURSON, OF CHICAGO, ILLINOIS, ASSIGNOR TO SIMPLEX STEEL PRODUCTS COMPANY, OF CHICAGO, ILLINOIS, A CORPORATION OF ILLINOIS.

TYING TOOL.

1,426,545.

Specification of Letters Patent. Patented Aug. 22, 1922.

Application filed July 31, 1920. Serial No. 400,497.

To all whom it may concern:

Be it known that I, HARRY H. BURSON, a citizen of the United States, residing at Chicago, county of Cook, and State of Illinois, have invented certain new and useful Improvements in Tying Tools, of which the following is a specification.

This invention relates to a tool adapted to bend sheet metal tongues as an incident to a tying operation. More particularly it is adapted for use with studdings of the general kind that are disclosed in my application heretofore filed December 11, 1919, as Serial No. 343,992. As an object of this invention I have aimed to produce a tool which may be used by the unskilled to effect a bending operation which is uniform in its results, the tool having special characteristics which adapt it to the particular use herein suggested.

In the drawing is represented an exemplification of this invention in the manner following:

Figure 1 is a view in perspective of two plaster boards tied to a studding by tongues which are bent with the present tool;

Figs. 2, 3, and 4 are side elevations of the tool shown in connection with the studding, three different stages in the bending operation being illustrated; and

Fig. 5 is a perspective view of the tool per se.

As an example of the use to which the present tool may advantageously be applied, I have shown in Fig. 1 a metal studding A to which plaster boards B are secured. In one wall of the studding are formed parallel slits 6 with a small opening 7 between them at one end. In this manner there is provided a tongue 8 which is bendable outwardly from the studding, the free end of the tongue being bendable upon itself as at 9, to grip a pin 10 that engages the outer side of the adjacent plaster boards to thereby tie them to the studding. It is with a tool that is specially adapted to effect the double bending of the tongue in this manner that my invention is concerned.

Referring now to Fig. 5, the tool comprises a pair of levers of the first class pivoted together as at 12. One end of each lever is formed with a handle portion 13, the two handles being disposed substantially parallel in the manner common to small hand tools. A spring 14 may be arranged be-

tween the handles, as shown, to normally hold them apart the maximum distance.

Each lever in the region of its intersection is appropriately recessed to provide a neck 15, and at its end is formed with a jaw that is disposed in a direction generally transverse to the medial line between the two handles. The two jaws are arranged in co-acting relation, one designated as 16 inside of the other 17, the inner jaw being extended outwardly a considerable distance beyond the other. At the point 18 where the outer jaw unites with the neck a stop is provided to limit the entry between the jaws of the tongue to be bent. Normally these two jaws remain open under the action of the spring 14, so as to freely receive the tongue, but when pressure is applied upon the handles the tongue is firmly clamped between the jaws. The outer jaw is further formed, as at 19, to co-operate with the inner jaw to provide a stop which limits the movement of the handles away from each other.

In the use of this tool in connection with a studding such as is shown in Fig. 1, the short outer jaw is inserted in the opening 7 preliminary to positioning the two jaws on opposite sides of the tongue 8. This stage of the operation is illustrated in Fig. 2. The final position of these jaws with the tongue between them is reached when the end of the tongue lodges at 18 against the neck adjacent the outer jaw as indicated in Fig. 3. In this position the end of the inner jaw is disposed just between the lower ends of the two slits 6 in the line of bend where the tongue is to project outwardly from the studding body. Having positioned the tool in this manner, the tongue is bent from the studding to the position of Fig. 3. The pin 10 is now set in place upon the tongue next to the end of the outer jaw. The tool is then reversed in its movement to bend the tongue upon itself and around the pin, as clearly shown in Fig. 4. During this last operation the pressure upon the handles is slightly reduced to permit the tongue end to slide out from between the jaws. In the final position of the tool, shown in Fig. 4, it is to be noted that its head end enters into the opening formerly occupied by the tongue, but may be readily withdrawn therefrom. As a result of the operations just described, the tongue is bent twice, the

first time at the exact line between the lower ends of the two slits 6, and the second time upon itself to curl around the pin which engages the plaster boards. The bending operations just described may accordingly be performed expeditiously and uniformly by means of the present tool which is specially constructed for this purpose.

I claim:

- 10 1. A tool of the kind described comprising a pair of pivoted levers each formed with a handle end, means for normally holding apart their handle ends, a jaw carried by each lever at its opposite end, both jaws being co-acting and disposed in a direction which is generally transverse to the medial line between the levers, the inside jaw being extended beyond the other, and a stop between the two jaws to limit the distance of entry of a tongue therebetween, the inside jaw having a length substantially equal to that of the tongue to be bent, substantially as described.
- 15 2. A tool of the kind described comprising a pair of pivoted levers of the first class having one end of each formed to provide a handle and the other end formed to provide a jaw which is disposed generally in a direction transverse to the medial line be-
- 20
- 25

tween the handles, the two jaws being of unequal length, the inside one being the longer, means between the jaws for limiting the entry of a tongue therebetween, the inside jaw extending outwardly from said limiting means a distance substantially equal to the length of the tongue to be bent, and spring means tending to hold the jaws apart, substantially as described.

3. A tool of the kind described comprising a pair of pivoted levers adapted for double bending of a sheet metal tongue, the two levers each having a handle end which substantially parallels the other, a pair of co-acting jaws carried by the two levers which are disposed in a direction generally transverse to that of the handles, the two jaws being of unequal length, the inside one the longer and substantially the same in length as the tongue to be bent, the length of the outer jaw being that of the tongue portion which is to be bent upon itself, and means between the jaws for determining the extent to which the tongue may be received between them, substantially as described.

HARRY H. BURSON.
